CLAIM

The ornamental design for a trowel box as shown and described.

DESCRIPTION

FIG. 1 is a front, left, and top perspective view of a trowel box, showing my new design;

FIG. 2 is a rear, right, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front, left, and top perspective view of the trowel box of FIG. 1 in a use state.

The broken lines depict portions of the trowel box in which the design is embodied that form no part of the claimed design.

1 Claim, 9 Drawing Sheets
